UNITED STATES PATENT OFFICE

CHARLES F. QUICK AND GEORGE W. TAMSITT, OF DALLAS, TEXAS

RELAY

Application filed April 30, 1928. Serial No. 273,884.

This invention relates to new and useful improvements in relays.

One object of the invention is to provide a relay for opening and closing an electric circuit in a simple and efficient manner.

Another object of the invention is to provide a relay having a short throw wiping contact which assures a positive connection at all times.

10 A particular object of the invention is to provide a relay having a comparatively few number of parts and employing a gravity contact, whereby electrical connection is effected without the use of spring contacts 15 and also whereby a short movement of the relay armature makes and breaks the circuit.

A construction designed to carry out the invention will be hereinafter described, together with other features of the invention,

20 The invention will be more readily understood from a reading of the following specifications and by reference to the accompanying drawings, in which an example of the invention is shown and wherein:

25 Fig. 1 is an elevation of a relay constructed in accordance with the invention and showing an armature swung to open the circuit,

Fig. 2 is a similar view showing the armature swung to close the circuit,

30 Fig. 3 is a transverse vertical sectional view taken on the line 3—3 of Fig. 1, and

Fig. 4 is a detail in plan of the contact bar and its mounting.

In the drawings the numeral 10 designates 35 a support which may be a plate or any other mounting suitable for the purpose. At each end of the plate a bracket 11 is fastened and an electro-magnet 12 is attached to the other bracket. The brackets and magnets may be 40 of any suitable construction. An armature 14 is pivoted to swing between the magnets so as to be alternately attracted thereby. The armature has a thin switch blade 15 at its upper end and a pivoted contact bar 16 45 rests upon the upper edge of said blade.

When the magnet 12 is energized and the armature 14 thus attracted the upper edge of the blade 15 will ride along the under surface of the bar 16 from the position shown in 50 Fig. 2 to the position shown in Fig. 1. An

insert 17 of insulating material is dove-tailed, or otherwise secured, in the bottom of the bar so that its exposed surface is flush with the bottom surface of said bar. It is essential that this insert be composed of some material 55 capable of withstanding wear substantially the same as the metal bar so as to constantly maintain the smooth and flush surface relation. We have found discarded talking machine record disks to provide an ideal material, but the invention is not to be limited to such material.

When the armature is swung by the magnet 12 the blade will ride from the bar 16 onto the surface of the insulating insert 17, thus 65 opening the circuit between the armature and said bar. When the magnet 13 is energized the parts will be moved to the position shown in Fig. 2, whereby the circuit between the armature and the bar will be closed.

70 The armature 14 is pivoted on a post 18 below the magnets, as is shown in detail in Fig. 3. This post has connection with one side of the circuit which it is desired to open and close. In order to prevent arcing and assuring a good contact, a light spring arm 19 fastened to the lower end of the armature constantly bears upon the rounded post and thus should the pivot connection of the armature become loose, an effective contact will 75 be maintained at all times.

The contact bar 16 is pivoted at one end upon a post 20 above the magnet 13 so that said bar will rest upon the blade 15, thereby 80 making a gravity contact. A spring arm 21 fastened on the bar constantly bears on the post 20 for assuring a circuit contact.

85 The post 20 has connection with the other side of the electrical circuit which it is desired to control through the armature and bar. The magnets 12 and 13 are, of course, separately controlled so that when the armature 14 is attracted the magnet circuit may be broken so as not to interfere with the circuit through the armature and bar.

90 The freedom of movement of the armature 14 and bar 16, the latter having only a minimum movement, is an important feature. The short stroke of the armature blade, 95 whereby the latter moves only a short dis-

tance from the bar to the insert 17, is of great advantage. The upper edge of the blade 15 is protected from dust and other accumulations because it is constantly covered by 5 either the bar 16 or the insert 17. The edge of the blade moving along the bottom surface of the bar 16 and the insert 17 provides a wiping contact which keeps these surfaces clean and assures proper functioning. The spring 10 arms 19 and 21 permit loose pivoting of the armature and bar, thus contributing to the free movement of said parts.

Various changes in the size and shape of 15 the different parts, as well as modifications and alterations, may be made within the scope of the appended claims.

What we claim, is:

1. In a relay, a pair of electromagnets, an armature mounted to swing between said 20 magnets, and a contact bar supported by said armature and having an insulating insert engaged by said armature when the latter is moved toward one magnet.
2. In a relay, a swinging armature, a contact bar resting on said armature and having electrical contact therewith, an insulating surface on the face of said bar engaged by said armature when the latter is swung, and means for swinging said armature.
3. In a relay, a swinging armature, a pivoted contact bar resting on said armature and having electrical contact therewith, spring 35 contact arms carried by the armature and bar and having contact with the pivotal mountings of said armature and said bar, an insulating insert in the face of said bar engaged by said armature when the latter is swung, and means for swinging said armature.
4. In a relay, a pair of electro-magnets, an armature mounted to swing between said 40 magnets, a contact blade carried by said armature at its free end, and a contact bar resting on the upper edge of said blade and having an insulating insert located to be engaged by the edge of the blade when the armature is swung toward one magnet.
5. In a relay, a pair of electro-magnets, an upright armature mounted to swing between 45 said magnets, a contact blade extending from the upper end of the armature, a horizontal pivoted contact bar resting upon the upper edge of the blade, and an insulating insert in the bottom of said bar located to be engaged by the upper edge of the blade when the armature is swung.

In testimony whereof we affix our signatures.

CHARLES F. QUICK.
GEORGE W. TAMSITT.
